UNITED STATES PATENT OFFICE.

ALBERT F. SAUNDERS, OF EAST SYRACUSE, NEW YORK, ASSIGNOR TO T. N. BENEDICT MFG. CO., OF EAST SYRACUSE, NEW YORK, A CORPORATION OF NEW YORK.

DESIGN FOR A DRINKING CUP.

Application filed August 3, 1921. Serial No. 489,638. Term of patent 3½ years.

o all whom it may concern:

Be it known that I, ALBERT F. SAUNDERS, citizen of the United States, residing at East Syracuse, in the county of Onondaga, and State of New York, have invented a new, original, and ornamental Design for a drinking Cup, of which the following is a specification, reference being had to the accompanying drawings, forming a part here-

Figures 1 and 2 are elevations of this cup taken at a right angle to each other.

I claim:

The ornamental design for a drinking cup, substantially as shown.

In testimony whereof, I have hereunto signed my name, at East Syracuse, in the county of Onondaga, and State of New York, this 16th day of July, 1921.

ALBERT F. SAUNDERS.
